UNITED STATES PATENT OFFICE

2,498,465

EXTENSION DRIVE SHAFT AND HANDLE
GRIP FOR ROTATABLE AND ANGULARLY
ADJUSTABLE TOOLS

James M. Thomas, Oklahoma City, Okla.

Application February 12, 1948, Serial No. 7,801

1 Claim. (Cl. 145—466)

1

This invention relates to new and useful improvements in wrenches and the primary object of the present invention is to provide a wrench bar including a tool engaging element and novel and improved means for adjusting the tool engaging element at selected angles relative to the wrench bar, for use in removing nuts or the like which are disposed in restricted areas which are difficult to reach by socket wrenches, or the like.

Another object of the present invention is to provide a wrench including a tool engaging member and embodying novel and improved means for retaining the tool engaging member at a selected angle and for rotating the tool engaging member in a convenient manner by an operator.

Another important object of the invention is to provide a wrench so designed as to permit a mechanic's hands to be unobstructed and clear from the work element in close places, thereby enabling the mechanic to work with better vision and freedom than was heretofore possible with the use of socket wrenches, or the like.

A further object of the present invention is to provide a wrench including a tool engaging member, an actuating bar connected to the tool engaging member, and novel and improved removable lever means for increasing the length of the present wrench and for effecting a rotation of the actuating member in places where the normal length of the wrench is impractical and inadequate.

A still further aim of the present invention is to provide a wrench that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary side elevational view of the wrench constructed in accordance with the present invention, the extension removed therefrom, and showing the tool engaging member in a raised position;

Figure 2 is a fragmentary side elevational view of the present wrench showing the tool engaging member in an inclined and partially lowered position, and with parts of the wrench broken away and shown in section;

Figure 3 is a fragmentary bottom view as indi-

cated by the arrows on the line 3—3 of Figure 1; Figure 4 is a transverse vertical sectional view taken substantially on the plane of the section line 4—4 of Figure 2;

Figure 5 is a fragmentary side elevational view of the present wrench in slightly modified form;

Figure 6 is a fragmentary longitudinal horizontal sectional view taken substantially on the plane of section line 6—6 of Figure 5;

Figure 7 is a view similar to Figure 5, and showing the removable lever extension applied thereto; and,

Figure 8 is a perspective view of the removable lever extension used in conjunction with the present invention.

Referring now to the drawings in detail, and more particularly to Figures 1—4 inclusive, wherein for the purpose of illustration there is disclosed a preferred embodiment of the present invention, the numeral 10 represents a tubular guide sleeve which is integrally formed with an enlarged cylindrical hand-grip 12 at one end.

Slidably and rotatably positioned in the guide sleeve 10, is an actuating bar or shaft 14, the forward end 18 and rear end 16 of which project outwardly from the guide sleeve 10 and the hand-grip 12. Fixed on the rear end 16 of the actuating bar 14 by any suitable means, is a preferably annular hand gripping knob 20 having an annular recess 22 in one end for engaging a socket element 24 integrally formed with the rear end 16 of the actuating bar 14.

Secured in a usual manner to the forward end 18 of the actuating bar 14, is a conventional single universal joint 26, one end 28 of which is integrally formed with the enlarged annular head portion 30 of a tool engaging lug 32. An annular bearing surface 34 integrally formed with the lug 32 is disposed between the head portion 30 and the lug 32 and removably engages

40 a fixed thrust or stop collar 36. Disposed between the stop collar 36 and the end 28 of the universal joint 26, is a bearing plate 38 having a central opening that rotatably receives the head portion 30 of the tool engaging lug 32. This bearing plate 38 is provided with an integral attaching ear 40 which is pivotally secured by a pin or the like 42 to the lower forward ends 44 of a pair of spaced parallel links 46, the rear ends 48

45 of which are pivoted on opposite sides of a rigid attaching ear 50 depending from the guide sleeve 10, by a pivot pin 52.

In practical use of the device thus described in Figures 1—4 inclusive, by holding the hand-grip 12 fixed and pushing the hand receiving

knob 20 forwardly, the socket engaging lug 32 will pivot downwardly to a selected inclined position relative to the actuating bar 14, as shown best in Figure 2 of the drawings, so that the lug 32 when applied to a suitable socket tool may remove nuts or the like which are disposed in restricted areas which would otherwise prevent a socket wrench or the like to be extended thereto. This tool engaging lug may be disposed at an inclined angle between the limits of zero degrees and forty-five degrees in the form of the invention shown in Figures 1-4 inclusive.

By rotating the knob 20, the actuating bar 14 will also be rotated to effect a rotation of the lug 32 and the suitable tool which is frictionally retained on said lug 32.

Reference is now directed to Figures 5 and 6, wherein there is disclosed the present invention in slightly modified form. In this embodiment, the numeral 54 represents the actuating bar or shaft which is slidably and rotatably mounted in a tubular guide sleeve 56 having a hand engaging grip 58 integrally formed at one end.

Removably secured to the actuating bar 54, is a usual, double universal joint 60, an outer section 62 of which is integrally formed with an enlarged head portion 63 of a tool engaging lug 64. The head portion of the lug 64 is rotatably mounted in an opening formed in a bearing plate 66 which is provided with a bifurcated extension 68 that supports a pivot pin 70. This pin 70 is pivoted to the forward free end 72 of a downwardly and forwardly inclined thrust arm 74 that is rigidly carried by the guide sleeve 56.

In practical use of this modified form of the invention, as shown in Figures 5 and 6, the actuating bar 54 is pushed forwardly by a hand grip 76 carried by said bar 54, and the guide sleeve 56 is held fixed so that the lug 64 will be pivoted relative to the arm 74 a selected angle, between the limits of zero degrees and ninety degrees. By rotating the grip 76, the bar 54 and lug 64 will likewise be rotated to effect rotation of a suitable tool or socket member which is positioned on the lug 64 thus permitting the convenient removal of nuts or the like with the tool engaging member disposed at a selected angle relative to the longitudinal axis of the actuating bar 54.

Reference is now directed to Figures 7 and 8, wherein there is disclosed the removable extension lever which is employed in conjunction with the present wrench, either the preferred form of the wrench shown in Figures 1-4 inclusive or the modified embodiment of the invention as shown in Figures 5 and 6. This extension which is des-

gnated generally by the numeral 78, includes an auxiliary guide sleeve 80 that rotatably and slidably supports an auxiliary actuating bar 82 having a socket engaging forward end portion 84 that frictionally engages the socket, either 24 or 36, formed at the rear ends of the actuating bars 14 and 54.

Rigidly secured to the auxiliary guide sleeve 80, is the angulated end 88 of an arcuate connecting arm 90 having a socket engaging lug 92 formed at its free end that frictionally engages sockets 94 which are integrally formed with the guide sleeves 10 and 56.

Fixed on a rear socket end 96 of the auxiliary actuating bar 82, is a knob 98 which may be conveniently rotated for effecting a rotation of either the bar 14 or 54, depending on which embodiment of the invention the present auxiliary or lever extension is applied.

It is noted that the auxiliary lever attachment 78 which is shown in Figures 7 and 8, is so designed as to facilitate the same to be quickly applied to or removed from either of the embodiments of the wrench described and shown.

Having described the invention, what is claimed as new is:

An extension handle and drive for a tool comprising a main guide sleeve, a shaft slidably and rotatably mounted in said main guide sleeve, tool engaging means pivotally connected to said main guide sleeve and to said shaft for movement between positions coaxial, and angular to, said shaft, the angular disposition of said tool engaging means relative to said shaft being varied by relative sliding movement between said shaft and said main guide sleeve, a removable auxiliary guide sleeve mounted on said main guide sleeve in coaxial and spaced relation thereto, and means slidably and rotatable in said auxiliary guide sleeve and connected to said shaft for rotating said shaft and tool engaging means.
